(57) **CLAIM**

The ornamental design for a concealing holster, as shown and described.

DESCRIPTION

FIG. 1 is a front perspective view of a concealing holster shown in accordance with my new design;

FIG. 2 is a rear perspective view of the concealing holster shown in FIG. 1;

FIG. 3 is a front elevation view of the concealing holster shown in FIG. 1;

FIG. 4 is a rear elevation view of the concealing holster shown in FIG. 1;

FIG. 5 is a left side elevation view of the concealing holster shown in FIG. 1;

FIG. 6 is a right side elevation view of the concealing holster shown in FIG. 1;

FIG. 7 is a top plan view of the concealing holster shown in FIG. 1; and,

FIG. 8 is a bottom plan view of the concealing holster shown in FIG. 1.

The features shown in dot-dash broken lines are for the purposes of showing boundaries of the design and form no part of the claimed design. The features shown in dash-dot broken lines illustrate portions of the concealing holster which form no part of the claimed design.

1 Claim, 8 Drawing Sheets
